UNITED STATES PATENT OFFICE.

JAMES W. COLLINS, OF NEW MARTINSVILLE, WEST VIRGINIA.

DESIGN FOR A PITCHER OR SIMILAR ARTICLE.

SPECIFICATION forming part of Design No. 36,170, dated December 16, 1902.

Application filed October 30, 1902. Serial No. 129,489. Term of patent 3½ years.

To all whom it may concern:

Be it known that I, JAMES W. COLLINS, of New Martinsville, Wetzel county, West Virginia, have invented a new, original, and ornamental Design for a Glass Pitcher or Similar Article, of which the following is a full, clear, and exact description, reference being had to the accompanying drawings, forming part of this specification, in which—

10 Figure 1 is a side elevation of a pitcher embodying my design, and Fig. 2 is a horizontal section on the line II II of Fig. 1.

The essential feature of my design consists in a pressed-glass pitcher or similar hollow glass article having a body provided with vertically-extending curved panels or columns with ornamental designs in intaglio or sunken in the glass.

In the drawings, 1 shows a pressed-glass pitcher having its body provided with a series 20 of vertically-extending panels or columns 2, which are transversely curved and separated by grooves or depressions 3. Each of these panels is provided with a pattern 4, which is in intaglio or sunken into the glass. 25

I claim—

The ornamental design for a pitcher or similar article as herein shown and described.

In testimony whereof I have hereunto set my hand.

JAMES W. COLLINS.
